J. COOK.
ANTIRATTLER BRAKE SHOE.
APPLICATION FILED SEPT. 26, 1918.

Patented Jan. 7, 1919.

UNITED STATES PATENT OFFICE.

JUDSON COOK, OF ALBANY, NEW YORK.

ANTIRATTLER BRAKE-SHOE.

1,290,098.

Specification of Letters Patent.

Patented Jan. 7, 1919.

Application filed September 26, 1918. Serial No. 255,807.

To all whom it may concern:

Be it known that I, JUDSON COOK, a citizen of the United States, residing at Albany, in the county of Albany and State of New York, have invented certain new and useful Improvements in Antirattler Brake-Shoes, of which the following is a specification.

This invention is an anti-rattler brake shoe, the object being to provide an improved form of backing plate and novel locking plate to firmly fasten the key, whereby the brake shoe may be secured to the brake head.

The invention comprises a locking plate of novel form which is provided with clamping lugs to engage a novel form of backing plate. The backing plate is provided with a perforated centrally positioned key-lug, the upper face of which is directed downwardly toward an upwardly directed portion of the locking plate, whereby when the locking plate and backing plate are assembled on the shoe, the said downwardly and upwardly directed portions of said plates will firmly and frictionally engage a locking key when passed through the perforations of the key-lug and thereby retain the locking key in position.

Other features of novelty will become apparent from the following detailed description of the invention, taken in connection with the accompanying drawing, wherein one embodiment of the invention is illustrated.

35 In the drawings,—

Figure 1 is a longitudinal sectional view through the shoe illustrating the invention assembled.

Fig. 2 is a longitudinal sectional view of the backing plate.

Fig. 3 is a top plan view of the backing plate.

Fig. 4 is a longitudinal sectional view of the locking plate.

45 Fig. 5 is a top plan view of the locking plate.

Fig. 6 is a sectional view on the line 6—6 of Fig. 4 of a winged end of the locking plate.

50 The shoe, 1, may be of any approved form and material, having the usual tread T, and may be provided with the key bearing lugs 2.

The backing plate 3 may be of resilient material and is shown curved throughout its length. This plate is provided with slots 4, 4, and with a centrally positioned up-

standing portion 5, forming a securing lug, provided with perforations 6 in the side walls of the portion 5. The top wall 6 of this portion 5 is preferably depressed and curved as at 7, the curved section being shown as concavo-convex in form. This backing plate 3 is preferably anchored to the shoe between the bearing lugs 2, 2 in any suitable manner.

65 The locking plate 8 is also shown as curved longitudinally with a convex-concavo centrally positioned bearing portion 9, which portion 9 may seat upon a protuberance 10 of the shoe 1. The locking plate 8 is shown provided with winged ends formed by the lugs 11 bent upwardly from the plane of the body of the plate 8. Four of these lugs are shown. These lugs 11 are passed through the slots 4 of backing plate 3 and thence positioned to ride upon, or have 70 slideable engagement with, a section 12 of the backing plate 3, adjacent the slots 4, the lugs 11 being positioned a suitable distance from the substantially vertical walls containing 75 the perforations 6 to prevent the lugs from coming into contact with the brake-head (not shown) when the device is thus assembled. Furthermore, the ends of the plate 8 may be notched as at 13.

80 The locking plate 8 may be suitably anchored on the shoe 1 with its winged lugs 11 engaging the backing plate 3 to maintain them in co-operative relation. When it is desired to secure the brake shoe to the 85 brake head, a locking key 14 is employed. This key 14 may be of flexible material and is shown curved and tapered throughout its length, terminating with the usual lug 15 at one end. The key 14 bears upon the lugs 2 and is passed through suitable portions of the break-head (not shown) and through the securing lug or upstanding portion 5 of plate 3, with the central part of the key 14 clamped between the depending arcuate portion 7 of plate 3 and the upstanding arcuate portion 9 of plate 8.

90 It is obvious that various changes in the form and proportion of parts may be made without departing from the spirit of the invention, and the right is reserved to make such changes as fairly fall within the scope of the appended claims.

Having thus described the invention, what is claimed as new is:

110 1. A brake shoe having a body, a backing plate secured thereto, a locking plate, and a

locking key; the backing plate being provided with a centrally positioned upstanding portion having perforated side walls and a concavo-convex top wall, and provided 5 with slots adjacent the upstanding portion, the locking plate having a convex-concavo central portion to coöperate with the concavo-convex wall of the backing plate in frictionally engaging an interposed locking key, 10 the locking plate having winged ends which enter through and ride upon the backing plate adjacent the slots to retain the locking and backing plates in coöperate relation.

2. In a brake shoe, a backing plate having 15 an upstanding perforated section forming a securing lug for a locking key when passed through the perforated section, said backing plate having slots formed on each side of the securing lug, a locking plate engaging the

lower face of the backing plate to be positioned between said plate and the brake shoe, 20 said locking plate being provided with a plurality of lugs arranged in pairs and positioned on a plane different from that of the body of the plate, said lugs being passed through and riding upon an upper surface 25 of the backing plate adjacent said slots, and means to frictionally engage a locking key when passed through the securing lug of the locking plate, said means comprising coöperating sections of the backing plate and the locking plate.

In testimony whereof I affix my signature in the presence of two witnesses.

JUDSON COOK.

Witnesses:

MARGARET M. WADDELL,
MABEL C. CANTWELL.
